UNITED STATES PATENT OFFICE.

JOHN D. FRED MEIER, OF OSHKOSH, WISCONSIN.

TOY RAILWAY.

SPECIFICATION forming part of Letters Patent No. 268,920, dated December 12, 1882.

Application filed October 18, 1882. (No model.)

To all whom it may concern:

Be it known that I, JOHN D. F. MEIER, of Oshkosh, in the county of Winnebago and State of Wisconsin, have invented a new and Improved Toy Railway, of which the following is a full, clear, and exact description.

The object of my invention is to provide a new and improved toy railway, which affords great amusement to children and adults.

10 The invention consists in a board divided into tracks and depot-spaces of different colors by strips, and provided with switches, on which tracks, sliding locomotives, and cars are moved from one station-space to the other, on which 15 cars different-colored blocks are placed, which represent freight or passengers.

Reference is to be had to the accompanying drawings, forming part of this specification, in which similar letters of reference indicate corresponding parts in both the figures.

Figure 1 is a plan view of one side of the track-board of my improved toy railway. Fig. 2 is a plan view of the other side of the same.

The board A, which has its corners rounded, is provided with rim a, of rattan strips or other suitable material. By means of strips B, of rattan or other suitable material, tracks C are formed on the surfaces of the board, between which tracks sliding locomotives O and 25 flat cars D and box-cars E can be moved. If desired, the locomotives and cars can be provided with wheels. Switches F are provided to switch the cars from one track to another, as may be desired. The strips B also form 30 surrounded spaces on the boards, which spaces are called "depots," and have each a different color. Colored spots G between the tracks at the depots indicate where the trains must stop for each depot. On one surface of the board, 35 as shown in Fig. 1, I have provided five switches, F, and four depots, H¹, H², H³, and H⁴, each of a different color. In the other side of the board (shown in Fig. 2) I have provided four switches, F, and two depots, J¹, J², each 40 of a different color. Colored blocks K are used to represent the freight or the passengers. Each train consists of a locomotive, O, and two flat cars, D, and two box-cars, E. The trains can run on the tracks only, forward or 45 backward, and the tracks must always be kept perfectly clear. The trains are moved by hand 50

from one depot to the other. For instance, all the red blocks K can be removed to the red depot or to a blue depot, and in this manner numerous combinations can be made. Cars 55 can be switched off and shunted, and freight can be transported to and from the different depots.

The above-described game gives the child both mental and physical occupation and induces it to think of various interesting problems and to solve them in various ways.

This game will be found to be very useful in kindergartens to illustrate how cars are switched off, how trains are built up, &c. 65

Having thus fully described my invention, I claim as new and desire to secure by Letters Patent—

1. A toy railway made substantially as herein shown and described, consisting of a board 70 on which tracks are formed by strips secured on the board, which tracks are provided with switches, as set forth.

2. In a toy railway, the combination, with a board, of strips secured on the same and forming tracks and depot-spaces, and of switches formed on the board, substantially as herein shown and described, and for the purpose set forth. 75

3. The combination, with the board A, provided with marks G at the depots, of the strips B, forming tracks and depot-spaces, and of the switches F, substantially as herein shown and described, and for the purpose set forth. 80

4. The combination, with the board A, subdivided into tracks and depot-spaces by strips B, of the switches F, the locomotives O, the cars D E, and the blocks K, substantially as herein shown and described, and for the purpose set forth. 85

5. The combination, with the board A, having its surface divided into tracks and into depot-spaces of different colors, of the switches F, the locomotives O, the cars D E, and the blocks K, having different colors, substantially 90 as herein shown and described, and for the purpose set forth. 95

JOHN D. FRED MEIER.
